UNITED STATES PATENT OFFICE

MARSHALL H. BRADEN, OF ROCK ISLAND, ILLINOIS, ASSIGNOR TO THE NU-WAY CORPORATION, OF ROCK ISLAND, ILLINOIS, A CORPORATION OF ILLINOIS

CONTROL SYSTEM FOR BURNERS

Application filed March 30, 1927. Serial No. 179,429.

The present invention relates to control systems for burners, having particular reference to electrically operated control systems designed for automatically controlling the 5 operation of an oil or gas burner, the exercise of this automatic control being generally in accordance with the different temperature requirements imposed upon the furnace—or upon whatever device is being heated by the 10 burner. The invention has its principal field of utility in conjunction with oil or gas burners of the class employed for firing domestic heating plants used in homes, buildings, etc., and accordingly in the following description 15 I shall refer to such embodiment of the invention, but it will be understood of course that the broad features of the invention can be employed in conjunction with any type of burner heated furnace or like device where 20 automatic regulation is desired.

One of the principal objects of the invention is to simplify the circuit connections in these control systems, to the end of reducing the initial and maintenance costs of the burner 25 installation, as well as to assure greater reliability of operation. Heretofore, all of these automatic control systems with which I am familiar have each involved a complicated network of circuits which are a considerable 30 source of expense and trouble, both in installation and in the maintenance of the burner. In this regard, it is a further object of the invention to provide a control system wherein there are practically no un- 35 guarded intervals i. e. abnormal conditions when the proper cyclical operation of the burner might be interrupted or dangerous conditions allowed to develop.

Another object of the invention is to provide a burner control system wherein the entire system is capable of operating on the same voltage. That is to say, the various control circuits of the system are all capable of operating directly from the line voltage or 40 from the same voltage that operates the electric motor of the burner unit.

Another object of the invention is to provide an improved ignition control cooperating with auxiliary motor means, preferably 45 in the form of a motor operated fuel valve.

Another object is to provide an improved construction of circuit-breaker or safety switch and cooperating electrical connections, for opening the main supply circuit should ignition fail or combustion cease. 55

Other objects of the invention pertaining to different structural features of the apparatus will appear at length in the following description of the invention. In the drawings 60 accompanying this description:

Fig. 1 is a view, mainly diagrammatic, showing the general plan and arrangement of my improved control adapted to an oil burner, including the circuit connections by 65 which the current from a central source is supplied to the apparatus and utilized in its control.

Fig. 2 is a side view, partly in elevation and partly in section, showing the relation between the motor driven fuel shut-off valve 70 and the control box in which are housed the ignition and the safety cut-off switches.

Fig. 3 is a vertical sectional view through the fuel shut-off valve, taken on the plane of the line 3—3 of Fig. 2. 75

Fig. 4 is a front elevational view of the interior of the control box, showing the ignition and safety switches therein.

Fig. 5 is a vertical sectional view through the thermostatic element of the safety switch. 80

Fig. 6 is a horizontal sectional view through the control box taken just above the ignition switch.

Fig. 7 is an enlarged detail section taken on the plane of the line 7—7 of Fig. 6. 85

Fig. 8 is a simplified circuit diagram of the above control system, and

Fig. 9 is a view, mainly diagrammatic, showing the general plan and arrangement of my improved control system when adapted 90 to gas burning apparatus.

In Figure 1 I have illustrated the present control system as being arranged for exercising its control functions on an oil burner of the general construction disclosed in my copending application, Serial No. 14,151, filed March 9, 1925. It will be understood, however, that this particular burner unit has been chosen merely for illustrating a typical adaptation of the present control system, and 95 100.

that the system can be employed with equal advantage on practically any design of oil burner. This control system can also be employed in conjunction with a gas burner for 5 burning natural or artificial gas, as disclosed in Fig. 9 of the drawings, which I shall hereinafter describe.

In Fig. 1 a typical furnace or other heater is indicated at 12, in front of which is 10 mounted the motor driven burner unit 13 above referred to. This burner unit comprises an electric motor 14, a fan or blower 15 and an atomizing fuel pump 16, all axially aligned and connected together to form a unitary assembly which is mounted on a base 17 supported in front of the furnace. The impeller of the blower and the rotor of the rotary atomizing pump are both mounted on the armature shaft of the motor, or on shafts 15 20 coupled directly to this armature shaft, so that both of these elements rotate directly with the motor armature. The outlet of the blower discharges through a conduit 18 entering the combustion chamber of the furnace 25 through the front thereof. The fuel is conducted from the outlet port of the atomizing pump through a discharge pipe 19, which enters the conduit 18 and extends forwardly therein to a nozzle designed to spray the fuel 30 into the combustion chamber. In the particular construction of atomizing pump shown in my copending application, provision is made for admitting air to this pump for mixing with the fuel in the pumping 35 operation, such atomized mixture of fuel and air being discharged through the pipe 19 to the combustion chamber.

The step of igniting the fuel is preferably performed by first igniting a jet of illuminating gas through the operation of suitable 40 electrical ignition apparatus, and then employing this gas flame to ignite the discharged mixture of fuel and air. The gas supply means consists of a pipe 21 which enters the 45 air conduit 18 and extends forwardly therein to a suitable gas nozzle disposed to project its gas flame in proximity to the jet of fuel issuing from the fuel discharge pipe 19. This gas supply is controlled by a shut-off valve 22 50 interposed in the pipe line 21, such shut-off valve being electrically operated through the instrumentality of a solenoid 23 or other electrically actuated means. The spark ignition is obtained from a vibrator coil, or trans- 55 former, indicated at 24, the secondary winding thereof having one side grounded at 25 and having its other side connected through wire 26 leading out through the air conduit 18 to a sparking electrode 27 disposed in position to ignite the gas discharged from the gas 60 pipe 21.

The main thermostat to which the entire burner system must respond in meeting the heat requirements imposed upon the furnace 65 is indicated at 28. In the case of a domestic

heating plant this thermostat is usually located in the living quarters of the dwelling and is generally referred to as the room or house thermostat. It preferably comprises a mercury tube switch consisting of a glass tube 29 in one end of which are embedded two contact terminals 31 and 32. The tube contains a globule of mercury and when such tube is tilted in one direction, this mercury completes the circuit through the terminals 31 and 32, and when the tube is tilted in the other direction, the mercury flows away from such terminals and thus opens the circuit. This tube is supported in clips on a rotatable member 33, which is connected to a bi-metallic strip or any other suitable thermally responsive element, capable of giving the desired tipping movement to the tube.

Another of such mercury tube switches is indicated at 35 in Figure 1. This switch is responsive to the combustion of the fuel and exercises a supervisory or safety control over the entire system so that there is no possibility of the burner continuing to project liquid fuel into the furnace if ignition should fail or combustion cease. This switch, often referred to as the "stack control", preferably has the same arrangement of two contacts 36 and 37 embedded in one end of a glass tube containing a globule of mercury. The tube is arranged to be tipped into circuit opening or closing position through a thermostatic element, such as a twisted bi-metallic ribbon 38. This thermostatic element is arranged to project into the stack or into the furnace at any preferred point where it will respond quickly to combustion temperatures. The arrangement is such that when the thermostatic element 38 is cold, the tube 35 will be tipped to its open circuit position, and that as the thermostatic element responds to the temperatures of combustion in the furnace, the tube will be tipped to its closed circuit position.

Referring now to the control of the fuel supply to the burner unit 13, and to the relation that exists between this fuel control and the control of the ignition system, it will be observed from Figure 1 that the fuel supply pipe 41, communicating with the atomizing pump 16, has connection with a constant level float chamber 42. Any suitable fuel regulating valve 43 may be interposed in the pipe 41 for proportioning the richness of the fuel mixture. The chamber 42 contains any suitable float controlled valve mechanism whereby a substantially constant level of fuel is maintained in such chamber. Combined with the lower portion of this chamber is a straining chamber 44 housing any suitable straining screen. These two chambers are preferably carried by or form a part of the base 17. The fuel supply pipe which conducts the fuel from the supply tank to this straining chamber is indicated at 45. Inter-

posed in this pipe, preferably adjacent to the chambers 42 and 44, is a motor operated shut-off valve 46, Figs. 2 and 3. Supported in front of such shut-off valve is a control box 47 in which are housed the ignition and safety switches, this control box being preferably associated directly with the motor operated shut-off valve inasmuch as the electric motor of the latter is arranged to serve as a control unit both for the operation of the movable valve element and for the operation of the ignition switch. The shut-off valve and control box are preferably disposed in immediate proximity to the burner unit, such location facilitating the making of the pipe connections between the source of fuel supply and the burner, but it will be obvious that the shut-off valve and control box might have suitable mounting on the floor, ceiling, or wall at any other point, if desired.

Referring now to the details of construction of the shut-off valve, as shown in Figs. 2 and 3, such valve comprises an electric motor 48 and a lower valve housing 49. Formed integral with the frame casting of the motor is a lower boss portion 51 and an upper gear housing portion 52. A front cover plate 53 is removably secured to the motor housing, such cover plate having component parts completing the lower boss 51 and the upper gear housing 52. Extending vertically through the boss and gear housing is a reciprocable rod or stem 54 which supports the valve head 55 at its lower end and which extends out at its upper end through an opening in the top of the gear housing. This rod is guided in suitable bearing bosses 56 and 57 carried on the inner side of the removable cover 53. One side of the rod 54 has rack teeth 58 formed therein through which a drive is transmitted from the armature shaft of the motor 48 to such rod, this drive occurring through speed reduction gearing illustrated in Fig. 3. The armature shaft 59 extends into the gear housing and carries a pinion 61 which meshes with a large gear 62 suitably journaled in the housing. This large gear carries a pinion 63 which meshes with a second large gear 64 which is also suitably journaled in the housing and which carries a pinion 65. The latter pinion meshes with a third large gear 66 also journaled within the housing and carrying a pinion 67 which meshes with the rack 58. The arrangement is such that the driving rotation of the armature shaft will transmit a slow speed drive through the aforementioned gearing to the pinion 67, and will rotate the latter in a direction to drive the rack upwardly, thereby raising the valve 55 from its seat 68.

The inlet passageway 69 of the shut-off valve opens into a chamber 71 above the valve seat 68, and the outlet passageway 72 opens downwardly from below the valve seat, so that whatever pressure is effective on the fuel

will always assist in holding the valve to its seat. Disposed within the chamber 71 around the valve stem or rod 54 is a sylphon bellows 73. The lower end of the sylphon is soldered or otherwise secured by a fluid-tight joint to the head of the valve 55, and the upper end of this sylphon has an outwardly extending flange 74 which is clamped in a fluid-tight joint between the top of the valve housing 49 and the bottom of the boss 51. The free expansive and contractive movement of the bellows with the movement of the valve will maintain a hermetic seal between the oil passageways of the valve casing and the exterior of the casing, thereby preventing any possibility of leakage of the oil. A heavy compression spring 75 extends down into the sylphon, bearing at its lower end on the head of the valve or on a suitable abutment carried thereby, and bearing at its upper end against the underside of the guide boss 57, this spring normally tending to hold the valve down against its seat 68. A sleeve 76 surrounds the stem 54, inside of the spring 75, the lower end of such sleeve bearing on the head of the valve and the upper end thereof terminating a predetermined distance below the guide boss 57. The sleeve is adapted to strike the underside of such boss in the upward movement of the valve so as to serve as a stop for limiting the movement of the valve in this direction.

The motor 48 is of a type which can be held at a dead stall indefinitely on its circuit without injury to the motor and without an objectionable consumption of current. Certain types of small induction motors are typical of motors having this capability. When the motor is energized, the armature shaft through the speed reducing gearing raises the valve from its seat up to the point where the sleeve 76 abuts the underside of the boss 57. When this occurs the motor comes to a dead stall, the sustained torque of the armature shaft holding the valve in raised position and permitting a continuous flow of fuel to the burner. When such motor is cut off the line at the end of the burner operating cycle, the spring 75 forces the valve 55 down to its seat, the free rotation of the armature in the opposite direction permitting this downward movement of the rack.

Fastened to the projecting upper end of the rod 54 by a screw 78 is an arm 79 which extends forwardly over the top of the switch box 47. A long screw or bolt 81 threads through a tapped hole in this arm and passes down through an opening 82 in the top of the box, such bolt or screw having a suitable lock nut 83 for maintaining any desired vertical adjustment of the screw in the arm 79. The lower end of this screw is adapted to engage one end of a rock plate 84 which carries an ignition switch 85. This switch is also of the mercury tube type, consisting of a sealed glass

tube in one end of which are embedded two contacts 86 and 87. These contacts are connected through flexible conductors 108 and 108' with connector terminals 109 and 110 mounted on an insulating panel 95, the latter being suitably supported on the rear wall of the switch box. As will be hereinafter described, the ignition circuit has connection with these terminals 109 and 110. The mercury tube is supported in clips 88 fastened to the underside of the rocking plate 84, and such plate has a rearwardly extending arm 89 (Figs. 2 and 6) which is bent downwardly at its end to have bearing support on a pin 91 extending between two spaced bearing plates 92 and 93. Referring to Fig. 7, these two plates are spaced by posts 80, and one edge of the rearwardly extending arm 89 is preferably provided with projecting lugs 90 adapted to engage one of these posts to limit the rocking movement of the switch in each direction. The bearing plates 92 and 93 are suitably supported by spacing posts 94 on the back panel 95. A weight 96 is secured to the rocker 84 adjacent the left hand end thereof, such weight thereby tending to rock the ignition switch downwardly to the left to its circuit opening position. The action of this weight may be supplemented by a tension spring 97 connected between the front bearing plate 93 and the arm 89 which extends rearwardly from the rocker. It will be observed that the screw 81 engages the rocker plate at the right hand side of its center of rocking support so that when this screw is in its lower position, corresponding to the closed position of the fuel valve 55, the ignition switch will be tipped downwardly to the right to its circuit closing position, in opposition to the action of the weight 96 and spring 97. When the motor driven shut-off valve is operated to open the valve this screw 81 moves upwardly with the upward movement of the valve, thereby permitting the ignition switch to tip downwardly to the left, to the circuit opening position illustrated in dotted lines. The left hand end of the rocker plate 84 has a slot 98 therein through which extends a rod 99 having connection at its lower end with a suitable motion retarding device, such as the dash-pot 101. This dash-pot comprises a cylinder 102 suitably secured to the back wall of the control box, the upper and lower ends of which cylinder are closed by end heads 103 and 104 for confining a body of oil or other damping liquid therein. The rod 99 extends down through the upper end head 104 and has its threaded lower end screwing into the head of a piston 105. The rod is extended down below the piston to support a valve disk 106 which controls the by-pass ports 107 in the piston head. It will be seen from the foregoing that when the motor operated fuel valve is actuated, and the screw 81 is caused to move upwardly, as before described, the tipping of the ignition switch downwardly to the left under the action of the weight 96 and spring 97 will be retarded by the action of the dash-pot 101. This retarding action is so timed that the ignition switch will not tip to its circuit opening position until the ignition apparatus has had ample time to ignite the fuel. The circuit connections through which this timed ignition operation occurs will be hereinafter described in connection with the description of the entire control system.

Also mounted in the control box 47 is a safety or cut-out switch 111, which is arranged to cooperate with the combustion responsive switch 35 to cut off the entire burner apparatus at any time in its operating interval should ignition fail or combustion cease. As previously remarked, the purpose of this the combustion chamber with fuel. The safety control is to prevent continued operation of the blower and fuel pump in the absence of combustion, which, if not interrupted at such time would result in the flooding of the combustion chamber with fuel. The safety cut-out switch 111 is also preferably in the form of a mercury tube switch comprising a glass tube in one end of which are embedded two terminals 112 and 113 with which the contained globule of mercury is adapted to make or break contact. The tube is supported in clips 114 secured to a rocking plate 115 which has a rearwardly and downwardly extending arm 116 also supported on a pivot pin 117 between spaced bearing plates 118 and 119, substantially similarly to the pivotal mounting of the upper rocker plate 84. A weight 121 secured to the left hand end of the rocker plate normally tends to tip the cut-out switch downwardly to the left for opening the circuit through the terminals 112 and 113.

The tube is normally held in its circuit closing position, corresponding to the position shown in Fig. 4, by a thermally responsive latch bar 122. The upper end of this latch bar carries a screw 123 which is adapted to engage over the edge of a hook 124 depending from the right/hand end of the rocker plate 115. Such latch bar, Fig. 5, consists of a bi-metallic strip having its lower end anchored to a block of insulation 125, and having its intermediate portion subjected to the heating action of a resistance element 126. This resistance element preferably comprises a metallic cylinder secured at its rear end to an insulating block 128 and having diametrically opposite slots 129 cut therein, through which passes the bi-metallic strip 122, these slots being sufficiently large so that in no point of the flexure of the strip 122 will it contact with the shell or cylinder. Disposed within this cylinder is a sleeve 131 of insulation within which is confined the resistance material,

such as a plurality of carbon disks 132 or like resistance elements. The rear end of this stack of disks bears directly against the thermostatic strip 122 to transmit its heat thereto, and the front end of this stack engages with a metallic compressing disk 133. The latter disk has a stem 134 supported in a threaded cap 135 which screws over the threaded end of the cylinder 126. By screwing this cap inwardly or outwardly on the end of the cylinder, the pressure exerted on the carbon disks, and hence the resistance through such disks, can be varied to secure any desired heat transmission to the thermostatic bar 122. For establishing electrical connection between this thermostatically controlled cut-out switch and the exterior circuits, three terminals 137, 138 and 139 are mounted on the insulating panel 95. The first of these terminals 137 is connected through a flexible conductor 141 with the switch contact 112. The second of these terminals is connected through wire 142 to a binding post or other suitable connection 144 mounted on the metallic casing 126 of the heating resistance. This binding post is in connection through the casing and through the end cap 135 and pressure disk 133 with the outer end of the stack of carbon disks. The third terminal 139 is connected through wire 143 with a binding post 145 secured to the base end of the thermostatic latch strip 122. A flexible conductor 146 extends from this binding post 145 up to the other contact 113 of the circuit breaking switch 111. It will be observed that current conducted to the terminal 137 from an outside circuit will pass through conductor 141 to the switch and thence through such switch, assuming it to be tripped downwardly to the right to its circuit closing position, down through wire 146 to the binding post 145. From this point, part of the current will be conducted up through the thermostatic latch bar 122, thence through the carbon disks 132, pressure disk 133, casing 126 and binding post 144 and wire 142 to terminal 138. Part of the current conducted from the switch through conductor 146 to binding post 145 will also pass through wire 143 to the other terminal 139. The several control circuits of the system are preferably encased in conduits, owing to the fact that the entire system operates upon the high voltage of the house lighting circuit. Two of such conduits are shown entering the control box at 147 and 148, the former receiving the ignition circuit wires entering the control box and the latter receiving the wires which connect with the thermostatically controlled safety switch.

Referring now to the circuit diagrams shown in Figs. 1 and 8, I have, for facility of explanation, shown the motor circuit or main supply circuit, in heavy lines, and the

ignition circuit in light lines. The current for operating the system is taken from the usual house lighting circuit, the two wires 151 and 152 representing leads from such a circuit. For facility in describing the circuit connections, the wire 151 may be considered a common or live wire with which the main operating units of the system are normally connected. The burner motor 14 has one of its terminals permanently connected to this line, and the fuel valve motor 48 also has one of its terminals permanently connected to this line through wire 153. A wire 154 taps off this common wire 151 and enters the control box where it has connection with the terminal 109. This terminal connects through flexible conductor 108 with contact 86 of the ignition switch. With the switch in its closed position, corresponding to the normal non-operating condition of the burner, the circuit continues through the switch and through conductor 108' to terminal 110. From this terminal a wire 155 extends to the solenoid winding 23 of the gas valve 22. A wire 156 taps off this wire 155 and connects to one side of the primary winding of the ignition coil 24. It will thus be seen that when the burner is not functioning the four main operating units, consisting of the burner motor 14, the fuel valve motor 48, the gas valve solenoid 23 and the ignition coil 24, are all in direct connection with the live wire 151 of the supply circuit. To facilitate the explanation of the circuit I have shown the room thermostat 28 as being interposed in the wire 152 of this supply circuit, but it will be obvious that such thermostat might be interposed in the wire 151.

Tracing through the other side of the circuit from the room thermostat 28, the wire 152 is extended into the control box 47 where it makes connection with the terminal 137. From this terminal the circuit continues through wire 141 to the contact 112 of the safety switch. This safety switch is normally latched down in closed position, and hence the circuit continues from the other switch contact 113 through wire 146 to the binding post 145 at the base end of the thermostatic latch. Here the circuit divides, part of the current flowing through wire 143, and terminal 139 to a wire 157 which connects to the solenoid 23 of the gas valve 22. A branch wire 158 taps off this wire 157 and connects to the other side of the primary winding of the coil 24, so that this coil is energized simultaneously with the energization of the solenoid winding 23. From the binding post 145 the other part of the circuit continues up through the thermostatic latch bar 122, thence forwardly through the resistance disks 132 and back through casing 126, binding post 144 and wire 142 to outlet terminal 138. From here a wire 159 leads to

the other side of the burner motor 14, a branch wire 161 tapping off the wire 159 and connecting with the other side of the fuel valve motor 48 so that both motors are connected in parallel. It will be seen from the foregoing that by virtue of this divided circuit, branching each way from the binding post 145 at the base end of the latch bar, whatever current flows to the gas valve solenoid 23 and to the ignition coil 24 does not pass through the resistance disks 132, whereas all of the current flowing to the burner motor 14 and to the fuel valve motor 48 passes through such disks. As will herein-
15 after appear, this is the preferred arrangement as it ensures a substantially constant flow of current through the resistance disks whereby the time interval for heating the thermostatic latch bar to its unlatching temperature can be closely calculated, but, if desired, the current flow to the gas valve solenoid and to the ignition coil can also be arranged to pass through the resistance disks. The stack or combustion responsive
20 switch 35 has one of its contacts connected through wires 162 and 157 with the terminal 139 in the control box, and has its other contact connected through wire 163 with the wire 159 leading from control box terminal 138. This places the two contacts 36 and 37 of the combustion responsive switch directly in shunt across the resistance disks 132 through the wires 162 and 163. When the burner is not operating the stack switch 35
25 normally stands in open position and hence the shunt across the resistance disks is open at this time.

In the operation of the system it will be seen that with the room thermostatic switch 28 in its open position the supply circuit to the system will be interrupted, but as soon as this room thermostatic switch is moved to its closed position, by a predetermined lowering of the temperature in the house, the circuit is completed through this side of the line to the terminal 137 of the control box. From here the circuit continues through the safety switch 111 to the binding post 145 where it divides, as before de-
30 scribed, part of the current flowing through wire 157 to the gas valve solenoid 23 and ignition coil 24, and part of the current flowing up through the thermostatic latch bar 122, resistance disks 132, wire 142, terminal 138 and wire 159 to the burner motor 14 and fuel valve motor 48. As previously re-
35 marked, with the burner inert, the four operating elements are all normally connected to the live or common side 151 of the supply circuit, and hence when the room thermostatic switch closes all four of these operating units are simultaneously energized. Both
40 motors 14 and 48 instantly begin to operate, the burner motor 14 projecting fuel and air
45 into the furnace, and the shut-off valve mo-

tor operating to open the fuel valve and thereby permit the continued supply of fuel to the fuel chamber as fuel is drawn therefrom. The solenoid 23 of the gas valve 22 being simultaneously energized, the gas valve is caused to open to discharge gas through pipe 21; and the primary winding of the ignition coil being also energized at this time, the secondary winding thereof produces a spark at the sparking electrode, thus igniting the gas jet issuing from the pipe 21. This preliminary ignition operation actually precedes the delivery of the fuel to the combustion chamber owing to the inertia of the burner motor and the slight delay incident to the atomizing pump 16 coming up to operating speed. Hence the gas flame is existing in the combustion chamber when the fuel is projected into the chamber, whereby ignition of the fuel can occur instantly without the possibility of a charge of fuel accumulating in the furnace before ignition occurs.

Simultaneously with the opening of the fuel valve, the screw 81 is caused to move upwardly away from the rocker 84, whereby the weight 96 and spring 97 become effective on the ignition switch, tending to move the latter to its open position. This movement of the switch is very gradual, being retarded by the dash-pot 101, so that an appreciable time interval elapses after the raising of the screw 81, before the switch tips to open position i. e. that position where the globule of mercury rolls to the left away from the contacts 86 and 87. Preferably, the apparatus is set for an ignition interval of from 15 to 25 seconds. This may be lengthened or shortened as desired by threading the screw 81 up or down in the arm 79 to thereby vary the angular position which the mercury tube normally occupies in its closed position, a greater inclination in this direction requiring a longer time interval for the switch to move to open position, and a lesser inclination requiring a shorter time interval. It will be evident that when the ignition switch moves to open position the circuit through the wire 155 is broken and hence the gas valve 22 automatically closes and the ignition coil 24 ceases producing its spark at the sparking electrode 27. The purpose of definitely interrupting the ignition operation after a predetermined period of time is to prevent the possibility of the furnace accumulating a large charge of combustible mixture and then being fired by a tardy operation of the ignition apparatus with the consequent possibility of an explosion. During this initial operation of the burner, all of the current supplied to the burner motor 14 and to the fuel valve motor 48 is passing through the resistance disks 132, inasmuch as the stack switch 35 is open at this time. Hence these disks are being gradually heated and are transmitting their heat to the

thermostatic latch bar 122. The heat transmitted to the latch bar during the initial operation of the burner is not sufficient, however, to cause such latch bar to flex to its releasing position, the arrangement being such that heat must be conducted to this latch bar for an appreciable time period before it will flex sufficiently to clear the screw 123 from the hook 124. Assuming now that in accordance with the proper operation of the apparatus, ignition of the fuel has occurred, the heat produced by this combustion of the fuel will promptly act on the thermostatic ribbon 38 and through the expansion of this ribbon will cause the stack switch 35 to be tipped to closed position. This places such switch as a shunt across the resistance disks 132 whereby substantially the entire current supply for the two electric motors 14 and 48 is diverted through the lower resistance path afforded by the stack switch. Thereupon the heating effect of the resistance element is almost entirely eliminated, with the result that the transmission of heat to the thermostatic latch bar is discontinued and this latch bar hence remains in its latching engagement with the hook 124, thereby holding the safety switch in its normal closed position.

Assume, on the other hand, that through the existence of some abnormal condition the fuel has failed to ignite at the end of the ignition interval and that the burner is still projecting fuel into the combustion chamber, threatening to flood the same and cause the waste of a large quantity of fuel. At this time the absence of any temperature of combustion in the furnace and stack will result in the stack switch 35 remaining in its open position. Hence all of the current supplied to the two motors 14 and 48 will continue to pass through the carbon disk resistance element. The heat transmitted to the thermostatic latch 122 will cause this latch gradually to flex outwardly, until, after the lapse of a predetermined time interval the screw 123 will clear the hook 124, allowing the safety switch to rock to open position, thereby breaking the circuit of the entire system through conductor 146. The apparatus is so adjusted that the circuit breaking function of the safety switch will not occur until some time after the ignition apparatus has gone through its igniting operation, thus giving the ignition apparatus full opportunity to ignite the fuel before the safety cut-out will operate. Different adjustments of this cut-out switch for different time intervals of operation can be obtained by screwing the cap 135 inwardly or outwardly along the cylinder 126, and by adjusting the screw 123 in the latch bar 122. The safety cut-out will only be caused to operate through the existence of some abnormal condition preventing ignition of the fuel; and such operation of the safety cut-

out will completely disconnect the system from the supply line until the householder manually tips the safety switch back to its closed position to latch the hook 124 under the screw 123 of the thermostatic latch bar. At such time the householder can examine the apparatus to correct the abnormal condition which brought about the operation of the cut-out switch.

One such condition which will, of course, result in failure of ignition is the exhaustion of the fuel supply. If this should occur during the normal operation of the burner while the furnace was being heated, it is desirable that the needless rotation of the burner motor be stopped. Such will automatically follow at this time through the action of the stack thermostat 38, which will gradually cool off and cause the stack switch to move to open position. This of course opens the shunt across the carbon disk resistance element with the result that the current flow of both motors will, in passing through this resistance element, heat the thermostatic latch and thereby trip the safety switch 111.

Assuming that the burner is operating under normal conditions, when the temperature of the house, room or other point being heated is brought back to the predetermined maximum temperature, the room thermostat will open the main circuit wire 152 and the entire system will then cease operating. With the deenergization of the fuel valve motor 48, consequent upon the opening of the circuit wire 152, the fuel valve will automatically move to closed position, thereby positively cutting off further flow of fuel to the burner and preventing any possibility of leakage, and in such movement to closed position the fuel valve through the arm 79 and screw 81 will reset the ignition switch to its closed position, preparatory to the next cycle of operation of the system.

This action of the fuel valve in resetting the ignition switch to closed position every time the control circuit is broken safeguards the burner against various abnormal conditions. For example, if the source of power should fail while the burner is in operation, the ignition switch will be immediately reset to closed position so that as soon as power comes back on the line the ignition operation will recur with the restarting of the burner motor.

It will be observed that the entire system operates on the voltage of the house lighting circuit, or on the voltage that is supplied to the burner motor, thus avoiding the expense of a step-down transformer for the control system and the possibility of such transformer burning out. The use of switches of the mercury tube type in the various control circuits is one of the features that makes the operation of the control system on the higher voltages practical, these

switches being capable of handling the higher voltages without injurious arcing and without requiring the complication of quick-break mechanism.

5 In Fig. 9 I have illustrated this same general arrangement of control system adapted to gas burning installations. The burner motor 14 is eliminated from the control system, as well as the solenoid-operated gas valve 22—23, otherwise the system is generally 10 similar to the arrangement illustrated in Fig. 8. The gas is discharged into the combustion chamber through any suitable burner nozzle 166, in the arrangement shown this 15 nozzle discharging through an air induction tube 167 entering the front of the combustion chamber. The flow of gas to this nozzle is controlled by the motor operated shut-off valve 46, which is interposed at any desired point in the gas supply line leading to 20 the nozzle 166. The sparking electrode 27 is suitably positioned adjacent the end of the gas nozzle for igniting the gas. In the 25 operation of this embodiment, the motor operated shut-off valve is opened when the room thermostat 28 closes, with the result that 30 gas is discharged from the burner nozzle 166. The ignition circuit is energized simultaneously therewith for creating an igniting 35 spark at the electrode 27, this ignition operation being automatically interrupted after the lapse of a predetermined time period by the gradual tipping of the ignition switch under 40 the control of the dash pot 101, as before described. In the event of failure of ignition or 45 cessation of combustion, the stack switch 35 will either remain open or reopen and hence the safety cut-out switch 111 will break the entire control circuit. With the opening of the control circuit, consequent upon the opening of the room thermostatic switch 28, or of the safety cut-out switch 111, the valve element of the motor operated shut-off valve will return to its seat, thereby stopping the flow of gas to the nozzle.

While the construction and arrangement of control system hereinbefore described is in most respects the preferred embodiment of my invention, it will be understood that 50 such embodiment is merely exemplary and that numerous changes and rearrangements may be made therein without departing from the fundamental features of the invention.

What I claim as my invention and desire 55 to secure by Letters Patent, is—

1. In a control system for burners, the combination with a burner motor, of a main supply circuit therefor, thermally responsive means controlling said supply circuit, an electrically operated control unit adapted to be energized upon the energization of said supply circuit and comprising a moving element, having movement in two directions, an ignition circuit, an ignition switch controlling 60 the energization of said ignition circuit from

said supply circuit, said ignition switch normally being in closed position during the non-operating intervals of the burner, and means for controlling the position of said ignition switch, said means being operated by the 70 movable element in one direction only.

2. In a control system for burners, the combination of a rotating armature electric motor, a circuit therefor, ignition apparatus, an ignition switch controlling said ignition apparatus, means operatively connecting said motor with said ignition switch whereby when said motor is deenergized said switch is caused to return to and to remain in closed position, and when said motor is energized said switch is permitted to move to open position with a motion independent of the motion of said motor, and means for retarding the motion of said switch to open position.

3. In a control system for burners, the combination of a fuel pipe supplying fuel to the burner, a valve in said fuel pipe, ignition apparatus for igniting the fuel comprising an ignition coil having primary and secondary windings, a circuit for said primary winding, a switch in said circuit, electrically operated means for opening said valve, circuit connections for maintaining said electrically operated means energized during the operation of the burner, and means for transmitting the motion of said valve to said switch for moving the latter to closed position.

4. In a control system for burners, the combination of a fuel pipe supplying fuel to the burner, a shut-off valve in said fuel pipe, ignition apparatus for igniting the fuel comprising a coil having primary and secondary windings, a circuit for said primary winding, a switch controlling said circuit, said switch normally tending to move to open position, electrically operated means for opening said valve, spring means for closing said valve, and means responsive to the motion of said valve and cooperating with said switch for holding the latter in closed position while the system is non-operating.

5. In a control system for burners, the combination of a fuel pipe supplying fuel to the burner, a shut-off valve in said fuel pipe, ignition apparatus for igniting the fuel comprising a coil having primary and secondary windings, a circuit for said primary winding, a switch controlling said circuit, said switch normally tending to move to open position, electrically operated means for opening said valve, spring means for closing said valve, means for transmitting the motion of said valve in one direction to said switch for moving the latter to closed position, and means operating independently of said electrically operated means for retarding the motion of said switch to open position.

6. In a control system for burners, the combination of a fuel pipe supplying fuel to

the burner, a shut-off valve in said fuel pipe, ignition apparatus for igniting the fuel comprising a coil having primary and secondary windings, a circuit for said primary winding, a mercury tube type of switch in said circuit, said switch normally tending to move to open position, a rotating armature type of electric motor mechanically connected to open said valve, spring means for closing said valve, means for transmitting the motion of said valve in one direction to said switch for moving the latter to closed position, and means operating independently of said motor for retarding the motion of said switch to open position.

7. In a control system for burners, the combination of a fuel pipe supplying fuel to the burner, a shut-off valve in said fuel pipe, ignition apparatus for igniting the fuel comprising a coil having primary and secondary windings, a circuit for said primary winding, a switch controlling said circuit, said switch normally tending to move to open position, a rotating armature type of electric motor mechanically connected to move said valve to open position, spring means for closing said valve, means for transmitting the closing motion of said valve to said switch for moving the latter to closed position, and a dash-pot for retarding the motion of said switch to open position upon the opening of said valve.

8. In a control system for burners, the combination with a fuel pipe supplying fuel to the burner, of a main circuit, a thermostatic switch controlling said main circuit, said thermostatic switch being responsive to the temperature of the area being heated, a burner motor connected to said main circuit, a secondary motor connected to said main circuit, a valve interposed in said fuel pipe, means for actuating said valve by said secondary motor, said motor operating to a stalled condition for holding said valve open, an ignition circuit comprising ignition means, an ignition switch controlling the connection of one side of said ignition circuit to one side of said main circuit, and means responding to the motion of said valve for moving said ignition switch to one position.

9. In burner control apparatus, the combination of a main circuit, a thermostatic switch interposed in one side of said main circuit, said switch being responsive to the temperature of the area being heated, a burner motor connected across said main circuit, a motor operated fuel valve connected across said main circuit, an ignition circuit comprising ignition means, an ignition switch controlling the connection of one side of said ignition circuit to one side of said main circuit, and means operated by said motor operated fuel valve and adapted to hold said ignition switch in closed position during the non-operating intervals of the apparatus.

10. In burner control apparatus, the combination of a main circuit, a thermostatic switch interposed in one side of said main circuit, said switch being responsive to the temperature of the area being heated, a burner motor connected across said main circuit, a separate motor operated fuel valve connected across said main circuit, the motor operating said fuel valve being adapted to be operated to a stalled condition, an ignition switch having one contact connected with one side of said main circuit, means responding to said motor operated fuel valve for actuating said ignition switch, an ignition circuit leading from the other contact of said ignition switch and connecting with the other side of said main circuit, and an ignition coil having its primary winding connected to said ignition circuit.

11. In burner control apparatus, the combination of a main circuit, a thermostatic switch interposed in one side of said main circuit, said switch being responsive to the temperature of the area being heated, a burner motor connected across said main circuit, a motor operated fuel valve connected across said main circuit, an ignition switch having one contact connected with one side of said main circuit, means responding to said motor operated fuel valve for actuating said ignition switch, an ignition circuit leading from the other contact of said ignition switch and connecting with the other side of said main circuit, an ignition coil having its primary winding connected to said ignition circuit, and an electrically operated gas valve connected to and opening with the energization of said ignition circuit.

12. In a control system for burners, the combination of an ignition circuit, an ignition switch controlling said circuit and tending to move to open position, an electric control motor, and means operatively connected with said electric motor and with said switch to hold the latter in closed position whenever said motor is deenergized, said motor, when energized, rendering said holding means non-effective whereby to permit said switch to move to open position.

13. In a control system for burners, the combination of an ignition circuit, an ignition switch controlling said circuit, said switch tending to move to open position, an electric control motor, means for maintaining said motor energized during the operation of the burner, independently of the opening of said ignition switch, and a one-way operating connection between said control motor and said switch operative to transmit motion to said switch in only one direction, said operating connection permitting said switch to move in the opposite direction while said motor remains energized during the operation of the burner.

14. In a control system for burners, the

combination of an ignition circuit, an ignition switch controlling said circuit, said switch tending to move to open position, an electric motor, circuit connections for maintaining said motor energized during the operation of the burner, and a one-way operating connection between said motor and said switch operative to transmit motion to said switch only in a direction to close the same, said operating connection permitting said switch to move to open position while said motor remains energized during the operation of the burner.

15. In a control system for burners, the combination of an ignition circuit, an ignition switch controlling said circuit, said switch tending to move to open position, a spring arranged for holding said switch in closed position when the system is deenergized, and an electric motor operative when the system is energized to overcome said spring for permitting said switch to move to open position.

16. In a control system for burners, the combination of an ignition circuit, an ignition switch controlling said circuit, said switch tending to move to open position, time-controlled means governing the movement of said switch to open position, an electric motor, 30 and means actuated thereby and effective whenever the motor is deenergized to hold said switch in closed position, but removing its restraint from said switch when the motor is again energized so that the movement of 35 the switch to open position will be governed solely by said time controlled means.

17. In a control system for burners, the combination of a main circuit, an ignition circuit, an ignition switch controlling said latter circuit, means tending to move said switch to open position, time-controlled means governing the movement of said switch to open position, a spring operatively connected for moving said switch to closed 45 position, and an electric motor operative when energized by said main circuit to overcome said spring for permitting said switch to move to closed position under the control of said time-controlled means.

50 18. In a control system for burners, the combination of a main circuit, an ignition circuit, an ignition switch controlling said latter circuit, means tending to move said switch to open position, a dash-pot for retarding the movement of said switch to open position, a rotating armature control motor responsive to said main circuit, a rack adapted to be moved in one direction by said motor, a spring for moving said rack in the opposite direction, and means for transmitting the latter movement of said rack to said ignition switch whereby said switch is moved to closed position when said control motor is deenergized.

65 19. In a control system for burners, the

combination with a burner motor, of a main supply circuit therefor, thermally responsive means controlling said supply circuit, an electrically operated control unit adapted to be energized upon the energization of said supply circuit and comprising a moving element having movement in two directions, an ignition circuit, an ignition switch controlling the energization of said ignition circuit from said supply circuit, means utilizing the movement of said movable element in one direction for moving said ignition switch to closed position, said switch being retained thereby in closed position during the non-operating intervals of the burner, and means operating independently of said electrically operated control unit for retarding the movement of said switch to open position.

70 20. In a control system for burners, the combination of ignition apparatus comprising an ignition coil having primary and secondary windings, a circuit for said primary winding, a mercury tube type of switch in said circuit, said switch normally tending to tip to open position, a rotating armature type of electric motor adapted to operate to a stalled condition, thermostatic means controlling said electric motor, a one-way operating connection between said motor and said switch operative to transmit motion to said switch only in a direction to close the same, 80 said operating connection retaining said switch closed during the non-operating intervals of the burner, and dash-pot means for delaying the motion of said switch from its closed position to its open position.

85 21. In a control system for burners, the combination of a main circuit comprising first and second wires, a burner motor, an oil valve, a control motor for actuating said oil valve, both of said motors being connected in parallel across said main circuit, a room thermostat connected directly in said main circuit, a circuit breaker interposed in said main circuit between said room thermostat and said burner motor, said circuit breaker comprising an electrically heated element operatively connected to release said circuit breaker, said electrically heated element being connected in series in said first main circuit wire to have the motor current pass therethrough, a combustion responsive switch connected to establish a shunt across said electrically heated element, an ignition circuit having one side thereof connected to 95 said first main circuit wire on the line side of said electrically heated element, an ignition switch connecting the other side of said ignition circuit to the second main circuit wire, and means actuated by said control 100 motor for operating said ignition switch.

105 22. In a control system for burners, the combination of a main high voltage circuit, a burner motor, an oil valve, a control motor for actuating said oil valve, both of said 110

115

- motors being connected in parallel across said main high voltage circuit, a room thermostat connected directly in said main circuit, a circuit breaker interposed in said main circuit between said room thermostat and said burner motor, said circuit breaker comprising an electrically heated element operatively connected to release said circuit breaker, said electrically heated element being connected in series with one of said motors to have the motor current pass therethrough, a combustion responsive switch connected to establish a shunt across said electrically heated element, an ignition circuit having one side thereof connected to said main circuit on the motor side of said circuit breaker, an ignition switch controlling said ignition circuit, and means actuated by said control motor for operating said ignition switch. 20
23. In a control system for burners, the combination of ignition apparatus comprising an ignition coil having primary and secondary windings, a circuit for said primary winding, an ignition switch in said circuit, said switch normally tending to move to open position, a rotating armature type of electric motor mechanically connected to move said switch to closed position, circuit connections for said motor for maintaining the latter energized during the operation of the burner and after said ignition circuit has been opened, said switch remaining in closed position during the non-operating intervals of the burner, thermostatic means cooperating with the circuit connections for said motor for controlling the operation of the motor, said motor when energized operating to a stalled condition and permitting said switch to continue to move thereafter toward its open position, and means for retarding the motion of said switch to open position. 35
24. In a control system for burners, the combination of a fuel valve, means biasing said valve to closed position, a rotary electric motor arranged when energized to move said valve to and maintain it in open position against said biasing means, a power multiplying gear train connecting the rotor of said motor with said valve and operable in one direction by said biasing means, means for stalling said motor while energized with the valve in open position, whereby said motor will maintain the valve opened, said biasing means being sufficient to overcome the inertia of the motor and gearing train and move the valve to closed position when the motor is deenergized, an ignition circuit, an ignition switch controlling said circuit, and means utilizing the motion of said valve for moving said ignition switch to one position. 50
25. In a control system for burners, the combination of an ignition circuit, an ignition switch controlling said circuit, a fuel valve, a rotary electric motor operating through a fixed cycle of rotation, said motor when energized rotating in a forward direction through a substantially predetermined number of revolutions, spring means functioning when said motor is deenergized to rotate the motor backwardly in the opposite direction through substantially the same number of revolutions, means utilizing the rotation of said motor in the forward direction to move said fuel valve to open position, and means utilizing the motion imparted by said spring means in rotating said motor in the backward direction for moving said ignition switch to closed position. 70
26. In a control system for burners, the combination of an ignition circuit, an ignition switch controlling said circuit, a fuel valve, a rotary electric motor operating when energized to rotate in a forward direction through a substantially predetermined number of revolutions, spring means functioning when said motor is deenergized to rotate the motor backwardly in the opposite direction through substantially the same number of revolutions, means utilizing the rotation of said motor in one direction to move said fuel valve to one position, and means utilizing the motion imparted by said spring means in rotating said motor in one direction to move said ignition switch to one position. 80
27. In a control system for burners, the combination of an ignition circuit, an ignition switch controlling said circuit, a rotary electric motor operating when energized to rotate in one direction through a substantially predetermined number of revolutions, spring means functioning when said motor is deenergized to rotate the motor backwardly in the opposite direction through substantially the same number of revolutions, and means utilizing the motion imparted by said spring means in rotating the motor in one direction for controlling said ignition switch. 90
